UNITED STATES PATENT OFFICE.

OLE OLSEN, OF ELGIN, ILLINOIS.

WATCH BALANCE-SPRING.

SPECIFICATION forming part of Letters Patent No. 469,914, dated March 1, 1892.

Application filed October 7, 1891. Serial No. 408,027. (No model.)

To all whom it may concern:

Be it known that I, OLE OLSEN, a citizen of the United States, residing at Elgin, in the county of Kane and State of Illinois, have invented certain new and useful Improvements in Watch-Springs; and I do hereby declare the following to be a full, clear, and exact description of the invention, such as will enable others skilled in the art to which it appertains to make and use the same.

My invention relates to improvements in hair-springs for watches and time-keepers; and it has for its object to poise the hair-spring on the collet to insure more perfect time-keeping than can be secured with the ordinary construction and arrangement now in use. It has been customary to make the hair-spring of a number of coils varying from ten to sixteen and in some cases to increase 15 the limit, and the over-coils of such springs have been made in many different forms and shapes when neither theory nor practice seemed to be of any use, and the relative position of the over-coil to the inside half-coil 20 was never considered important. It has always been an easy matter to poise the balance-wheel; but to my knowledge a perfect poise of the hair-spring has never been accomplished. The spring has been secured to 25 the collet at zero; but as the over-coil cannot be counted because of its near approach to the center it gave twelve half-coils on one side and thirteen coils on the other. This construction has therefore prevented the poising 30 of the hair-spring and resulted in an error of time-keeping ranging from fifteen seconds upward.

My invention aims to construct the hair-spring in a peculiar manner to obviate these 40 objections just noted, to secure a perfect poise of the hair-spring, and to obtain more perfect time-keeping.

With these and other ends in view my invention consists in making a spring which has 45 the inside half-coil and the outside over-coil on the same side, whereby an even number of half-coils on each side is secured, as the over-coil is so near the center it cannot be counted as a half-coil.

To enable others to more readily understand my invention, I have illustrated the

same in the accompanying drawings, in which—

Figure I is an enlarged top plan view of my hair-spring with the balance and other parts 55 associated immediately therewith. Fig. II is an enlarged plan view of the hair-spring, and Figs. III and IV are side elevations showing the rise or elevation of the over-coil and its position relative to the other coils of the spring. 60

Referring to the drawings, in which like letters of reference denote corresponding parts in all the figures, A designates the hair-spring, which is secured on the collet B above the balance C in any desirable manner. 65

To enable others skilled in the art to more clearly understand my invention, I have applied the coiled spring to a chart having the principal degree-points on Fig. II, referring more particularly to which the spring is preferably fastened to the collet B at the point indicated at one hundred and eighty degrees or between one hundred and thirty-five degrees and two hundred and twenty-five degrees, and the first bend E of the over-coil is also arranged 70 at this point. This construction gives thirteen complete coils, more or less, as desired, which is the working part of the spiral as far as the poise of the main body of the hair-spring is concerned. 75

The balance and hair spring of a watch should be perfectly poised, to insure perfect time-keeping, in six positions—namely, dial up, dial down, and at the four equal divisions of the hour, XII, III, VI, and IX, up. The inside coils, out to the middle of the spiral or even more, are carried by the balance and amount to a good deal in weight. If there are not full coils from the starting-point in the collet to the first bend at one hundred 80 and eighty degrees, it puts the spring out of poise to the extent of the fractional coil. The first bend of the spring at one hundred and eighty degrees serves as a movable stud for the spiral, and it is carried by the over-coil, 90 which constitutes a flexible support therefor. If the regulator is dispensed with, the stationary stud d', now at three hundred and fifteen degrees, would have to be moved to zero, as that is the terminal end and working part 100 of the whole spring.

I have stated that the first bend of the over-

coil is at one hundred and eighty degrees, and this is my preferred construction; but I may make this bend and fasten the spring in the collet at any point between one hundred and thirty-five degrees and two hundred and twenty-five degrees, as may be found in practice to prove most advantageous. The over-coil then extends straight across the spring, and the ends of said straight piece *e* point, preferably, to 5 fifty-five degrees and one hundred and seventy degrees, and the second bend *E'* of the over-coil is located at or about the former point. The last circle *e* of the over-coil begins at or about fifty degrees and terminates at zero, 10 and should touch the straight line *f* drawn from five degrees to fifty degrees. In forming the over-coil the end is moved forward forty-five degrees, which will very closely give the length of the over-coil before forming it to 15 two hundred and twenty-five degrees. The increased weight occasioned by the straight portion of the over-coil is compensated by the last half-coil being farther from the center than the next last one, and the spring is thus 20 equally poised at the points ninety degrees and two hundred and seventy degrees. The first upward incline of the spring commences at two hundred and seventy degrees and gradually increases to the bend *E*, where it turns 25 across the spring and it may gradually increase, if desired. It will thus be seen that there is about one hundred and twenty-five degrees between the first bend *E* and second bend *E'*, and I prefer to arrange the bends so 30 that this number of degrees will intervene between them. This construction of the spring allows it to be equally poised, and it has been found that the error caused by the unequal 35

poise of the spring is reduced from fifteen to five seconds.

I am aware that changes in the form and proportion of parts and details of construction can be made without departing from the spirit or sacrificing the advantages of my invention, and I therefore reserve the right to 45 make such changes in the construction and arrangement of parts as fall within the scope of my invention.

Having thus fully described my invention, what I claim as new, and desire to secure by 50 Letters Patent, is—

1. A hair-spring for time-keepers, having the first half-coil and the over-coil arranged on the same side, substantially as and for the purpose described.

2. A hair-spring for watches, having the upward incline on the outer coil thereof, the bend on said incline at a point opposite where the spring is fastened to the collet, and the straight portion across said spring, substantially as described.

3. A hair-spring for time-keepers, having the first half-coil and the over-coil arranged on the same side of a line drawn through the collet and its outer coil provided with the upward incline, and the bend *E* on said incline opposite to the point where the inner end of the spring is fastened to the collet, substantially as described.

In testimony whereof I affix my signature in 70 presence of two witnesses.

OLE OLSEN.
